UNITED STATES PATENT OFFICE.

EMERY D. NELLIS, OF ST. LOUIS, MISSOURI, ASSIGNOR TO THE BRIDGE & BEACH MANUFACTURING COMPANY, OF SAME PLACE.

DESIGN FOR A STOVE.

SPECIFICATION forming part of Design No. 22,667, dated August 1, 1893.

Application filed July 1, 1893. Serial No. 479,393. Term of patent 7 years.

To all whom it may concern:

Be it known that I, EMERY D. NELLIS, a citizen of the United States, residing in the city of St. Louis, in the State of Missouri, have invented and produced a new and original Design for Stoves, of which the following is a full, clear, and exact description, reference being had to the accompanying drawing, wherein the figure represents a front view of a stove ornamented with my new and original design.

The design resides essentially in ornamenting a square-shaped stove with scrolls, substantially as shown.

The back-board, at the top and back of the stove, is formed with the rise in the middle of its upper edge, and is ornamented at said upper edge, and at its bottom with a row of beads. About the center of this back-board, is a rosette, which has projecting from its under side a number of single scrolls, in the form of two sprays, while on each side of the rosette and sprays are other scrolls, intertwining and overlapping each other as shown. Projecting forwardly from the ends of this back-board, are two side pieces which extend over the top-plate of the stove, which side pieces are ornamented with scrolls. The top plate terminates at its front and sides in a downwardly-projecting flange, on which flange is arranged a series of scrolls. The front of the body portion of the stove is substantially rectangular in shape, and is provided with four doors or slides, arranged in pairs, one above the other, and between which pairs a panel or space is left, suitable for a name or number. All these doors or slides are ornamented in like manner and the following description of one is applicable to all, and although but a portion of the lower pair is visible, still that portion which is shown will be seen to correspond with its companions above. The ornamentation of these

doors or slides consists in a centrally located rosette, from the under side of which is arranged a series of scrolls forming a spray on each side of the rosette, said sprays nearly meeting each other thereabove. Below these sprays are scrolls, so arranged, relative to the sprays, that the entire central ornamentation forms a rectangle, in the center of which is the rosette. Around this central ornamentation, the door or slide is formed with convexed portions, which are ornamented at about their middle outer edges with flutes arranged in the form of an open fan. Above and at the sides of these doors, is a number of scrolls, sprays, &c., which overlap and intertwine with each other, these scrolls being relieved at the upper portion of the stove above the doors with a fan-shaped figure, and, at the sides of the doors, with rosettes, one on each side, which fan-shaped figure and rosettes, the scrolls embrace with their members. The foot-rest projects upwardly and outwardly from the base of the stove, and is ornamented with scrolls on the upper face of its ends. The base-plate is formed with a plain downwardly-projecting flange, which plate and flange are bellied in their front middle portion. The legs are arranged on the front side corners of this base-plate, and at the back of the stove, which legs are ornamented on their upper outwardly curved portions with scrolls, having sprays leading therefrom, as shown.

What I claim is—

The design for a stove, substantially as herein shown and described.

In testimony whereof I hereunto affix my signature, in presence of two witnesses, this 27th day of June, 1893.

EMERY D. NELLIS.
